(57) CLAIM

The ornamental design for a beverage dispenser tower, as shown and described.

DESCRIPTION

FIG. 1 is a top, front, right perspective view of a beverage dispenser tower showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The uneven-length broken lines represent unclaimed boundaries of the claimed design. The even-length broken lines showing the remainder of the beverage dispenser tower are for environmental purposes only and form no part of the claimed design.

1 Claim, 7 Drawing Sheets
